W. G. McGuire

SHOE POLISHER

Filed March 10, 1924

P. J. Hickey

WITNESS:

W. G. McGuire,
INVENTOR
BY *Victor J. Evans*
ATTORNEY

UNITED STATES PATENT OFFICE.

WILLIAM GILFORD MC GUIRE, OF ST. LOUIS, MISSOURI.

SHOE POLISHER.

Application filed March 10, 1924. Serial No. 698,211.

To all whom it may concern:

Be it known that I, WILLIAM G. MC GUIRE, a citizen of the United States, residing at St. Louis, in the county of St. Louis and State of Missouri, have invented new and useful Improvements in Shoe Polishers, of which the following is a specification.

This invention relates to daubers for shoe polish, wherein the polish is contained within the dauber and adapted to be fed to the bristles from time to time as the occasion may require, the invention residing in the construction, combination and arrangement of parts as claimed.

15 In the drawing forming part of this application, like numerals of reference indicate similar parts in the several views, and wherein:

Figure 1 is a view in elevation of the 20 dauber constructed in accordance with the present invention.

Figure 2 is a sectional view taken on the line 2—2 of Figure 1.

Figure 3 is a sectional view taken on the 25 line 3—3 of Figure 1.

The dauber essentially consists of a container 10 preferably of cylindrical formation in cross section, and which container is of a size to permit of its being conveniently handled for the purpose intended. The container is reduced and threaded at one end as at 11, and screwed onto this end of the container is a cap 12 including a conical shaped portion 13 which terminates

35 to provide an annular flange 14, and the edge of which extends inwardly as at 15 for a purpose to be presently described. Carried by the cap 12 and disposed within the latter is a substantially conical shaped member 16 which forms a support for the polish or paste 17, and at the same time defines a restricted outlet opening therefor, the paste being fed through the bristles of the dauber through this opening as will be

40 readily understood. Supported by the cap 13 is a slide valve 18 adapted to control the discharge of the contents of the container as will be readily understood. This valve is mounted to slide across the restricted outlet opening for the contents, and includes a stem which can be conveniently

manipulated to either open or close the valve as the occasion may require. The small end of the conical shaped member 16 is turned upon itself to provide a bead 18, and as 55 clearly shown in Figure 2, the bristles 19 of the dauber are effectively clamped between this bead and the annular flange 14 and inwardly directed edge 15 of the cap. Arranged to slide within the container is a follower 20, the annular edge of which is grooved to receive a packing 21 which contacts the inner wall of the container. The upper end of the container is open to receive the hand of the user when it is necessary to move the polish 17 in a direction of the bristles 19, and this is accomplished by simply pressing upon the follower 20 which reposes upon the upper end of the polish or paste 17. Manifestly, a small portion of polish may be maintained in the position shown in Figure 2, wherein it will be noted that the polish or paste is arranged centrally of the bristles 19 and substantially flush with the lower or free ends of the 70 bristles, thus making it possible to apply the paste to the shoe without bringing the hand or fingers in contact with the paste, and at the same time assure a proper or equal distribution of the paste over the entire area of the shoe. The dauber is therefore meritorious from an economical point of view in that it eliminates waste of the polish, which cannot be easily prevented by the customary manner of applying paste to 75 the shoe by the hands or fingers.

80 While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

An article of the character described comprising a polish container, a cap detachably connected with one end of the container and including a conical portion terminating 100 to provide an annular flange, the lower edge of which extends inwardly, a substantially

conical shaped member arranged within and forming part of the cap and terminating in a plane with the end of said cap, said member defining a restricted outlet opening for the polish, the free end of said member being rolled upon itself to form a hollow flange rectangular in cross section, bris-

10 tles clamped between said hollow flange and the flange of said cap, a valve controlling said outlet opening, and a follower arranged to operate within the container.

In testimony whereof I affix my signature.

WILLIAM GILFORD McGUIRE.
